UNITED STATES PATENT OFFICE.

WILBUR R. CARROLL, OF BLOOMFIELD, IOWA.

FLUE-STOPPER.

1,397,753.

Specification of Letters Patent. Patented Nov. 22, 1921.

Application filed June 22, 1921. Serial No. 479,598.

To all whom it may concern:

Be it known that I, WILBUR R. CARROLL, a citizen of the United States, and resident of Bloomfield, Iowa, have invented new and useful Improvements in Flue-Stoppers, which invention is fully set forth in the following specification.

This invention relates to improvements in flue-stoppers and particularly to the type thereof in which a cover-plate is provided to close the flue-opening and is held in place by mechanism mounted on the inner side thereof, said mechanism extending into the flue-opening to engage the wall thereof and being actuated by means operable from the outer side of the cover-plate. Generally the object is the provision of a device of simple and cheap construction, which can be easily mounted in or displaced from the flue, which will firmly hold the cover-plate in place when mounted, and which will accommodate itself to flues having a wall of varying or different thickness around the flue opening. The aforesaid and other objects are attained by the present invention the more preferred embodiment whereof is illustrated in the accompanying drawing, wherein:

Figure 1 is a longitudinal sectional view showing the improved flue-stopper mounted in a flue having a wall of uniform thickness around the flue opening;

Fig. 2 is a similar view, showing the device mounted in flue having a wall of uneven thickness;

Fig. 3 is a longitudinal sectional view, showing the device displaced from the flue and the holding mechanism collapsed, the actuating screw-rod being removed.

Fig. 4 is a detail sectional view on the line 40 4—4 of Fig. 1.

As shown in the drawing, the cover-plate 1, preferably in the form of a disk, is of sufficient diameter to overlap the face of the wall adjacent to the flue opening. On the inner side of the cover-plate is riveted the flanged plate 2 in a central position. Extending through the flange of the plate 2 is the pin 3 on which are hinged or pivoted ends of the diverging links 4. These links are pivoted

or hinged at their free ends by the pins 5 to the inner ends of the crossed levers 6 pivoted or hinged together at their intersection by the pin 7. The inner ends of the levers, from their extremities connected with the links 4 to the pin 7, are approximately of the same length as the links so that these parts can be collapsed to a closed position as shown in Fig. 3. The outer ends of the levers, from the pin 7 to their outer extremities, are considerably longer than the links and the extreme ends are twisted and curved to form shallow hooks or bearing members 8 adapted to engage the inner face of the wall through which the flue passes.

In a central aperture 9 in the cover-plate 1 and the flanged plate 2 is loosely mounted the screw-rod 10 for actuating the holding mechanism. Inward movement of the screw-rod through the aperture is limited by its head 11 contacting with the cover-plate, and this head also serves as a handle for rotating the rod from the outer side of the plate. In operative position the screw-rod engages the threaded flange of the plate 12 pivoted on the pin 7 forming the pivot for the levers 6. As the screw-rod is rotated one way or the other and held against longitudinal movement the plate 12 is moved through its threaded engagement with the rod and carries the pin 7 with it. When the pin 7 is moved away from the cover-plate 1 the lazy-tongs, formed by the levers and links, is extended; when the pin is moved toward the cover-plate the lazy-tongs is retracted.

In mounting the device in a flue the screw-rod 10 is inserted in the aperture 9 in the cover-plate 1 and its end is turned a few turns into the threaded opening of the plate 12. With the rod so engaged it is pushed through the aperture to extend the lazy-tongs, which is then inserted in the flue opening and the cover-plate is positioned against the wall over said opening. The lazy-tongs being so positioned, the hooks 8 on the ends of the levers 6 extend beyond the inner face of the wall. The screw-rod 10 is then rotated to move the plate 12 toward the cover-plate. This movement of the plate

12, carrying with it the pin 7 on which are pivoted the levers 6, retracts the lazy-tongs. As the lazy-tongs is retracted the levers 6 are opened and the hooks 8 are projected 5 over the inner face of the wall. In the retraction of the lazy-tongs the head 11 of the screw-rod 10 bears on the closure-plate 1 to limit the inward movement of said rod and a strong pull is exerted on the plate 12 and thereby the hooks 8 are firmly pressed 10 against the inner face of the wall to hold securely the closure-plate in place over the flue opening. To release the device the screw-rod 10 is turned to move the plate 12 away from the closure-plate 1 and this movement of the plate 12 extends the lazy-tongs 15 to disengage the hooks from the wall so that the device can be withdrawn from the flue opening. To facilitate packing and storing 20 the screw-rod is turned to clear the plate 12 and is withdrawn from the closure-plate. The device is then compactly collapsed as shown in Fig. 3, with the hooked ends of levers 8 approximately even with the peripheral edge of the cover-plate.

It is to be observed that the lazy-tongs, as a whole, is pivoted on the pin 3 so that it can be moved laterally thereon. To accommodate this lateral movement the screw-rod 10 30 has a loose fit in the aperture 9 of the cover-plate so that it can follow the lateral displacement of the lazy-tongs. This lateral displacement of the lazy-tongs permits the use of the device in flue-openings having 35 uneven thickness in the wall on opposite sides of the flue-opening, as shown in Fig. 2. The hooks 8 have considerable length to insure a bearing engagement at their extremities on the inner face of the wall irrespective 40 of lateral displacement of the lazy-tongs. It is to be noted that the engagement of the hooks with the inner face of the flue wall is not effected by a wedging action of the mutually pivoted levers 6, but by a direct 45 pull imparted to the hooks by the contraction of the lazy-tongs as a whole. This direct pull of the hooks insures a tight closure of the cover-plate over the flue opening without straining any of the parts.

The screw-rod 10 is preferably made of wire bent to form the loop or head 11 and two lengths which are twisted together to form the screw-threaded portion. The rod so formed is much cheaper than if made of 55 a single length of wire with threads cut therein.

What is claimed is:—

1. In a flue-stopper, the combination with 60 a cover-plate for the flue opening in a wall, of diverging links hinged at one end to the cover-plate, crossed levers pivoted together at their intersection and hinged at their inner ends to the free ends of said links respectively and adapted to engage the wall in which the flue opening is formed to secure 65

the flue-stopper in place, and means for actuating the jointed links and levers to engage the levers with said wall to hold the cover-plate in place with relation to the flue opening. 70

2. In a flue-stopper, the combination with a cover-plate for the flue opening in a wall, of diverging links hinged at one end to the cover-plate, crossed levers pivoted together at their intersection and hinged at their inner ends to the free ends of said links respectively and adapted to engage the wall in which the flue opening is formed to secure the flue-stopper in place, and a rotatable rod 75 extending through the cover-plate and having a screw-threaded connection with said levers so that the rotation of the rod will actuate the jointed links and levers to engage said levers with said wall to hold the cover-plate in place with relation to the flue-opening. 80

3. In a flue-stopper, the combination with a cover-plate for the flue opening in a wall, of diverging links hinged at one end to the central part of the cover-plate, crossed levers 90 pivoted together at their intersection and hinged at their inner ends to the free ends of said links respectively and adapted to engage the wall in which the flue opening is formed to secure the flue-stopper in place, a 95 plate pivoted to the crossed levers at their intersection, and a rotatable rod extending through the cover-plate and having a screw-threaded engagement with said plate so that the rotation of the rod will move said plate 100 to actuate the jointed links and levers to engage said levers with said wall to hold the cover-plate in place with relation to the flue opening. 105

4. In a flue-stopper, the combination with a cover-plate for the flue opening in a wall, of a lazy-tongs hinged at one end to the central part of the cover-plate and adapted at its other end to engage the wall in which the flue opening is formed to secure the flue-stopper in place, said lazy-tongs being laterally displaceable to accommodate itself to a flue opening in a wall of varying thickness around said opening, and means for retracting the lazy-tongs to move the same 115 into engagement with said wall to hold the cover-plate in place over the flue opening. 120

5. In a flue-stopper, the combination with a cover-plate for the flue opening in a wall, of a lazy-tongs hinged at one end to the central part of the cover-plate and adapted at its other end to engage the wall in which the flue opening is formed to secure the flue-stopper in place, said lazy-tongs being laterally displaceable to accommodate itself to a 125 flue-opening in a wall of varying thickness around said opening, and a rod loosely mounted in the cover-plate to move longitudinally therein and connected with the lazy-tongs and operable to retract the lazy-tongs 130

- tongs to move the same into engagement with said wall to hold the cover-plate in place over the flue opening.
6. In a flue stopper, the combination with a cover-plate for the flue opening in a wall, of a lazy-tongs comprising diverging links hinged at one end to the central part of the cover-plate and crossed levers pivoted together at their intersection hinged at their inner ends to the free ends of said links respectively, said lazy-tongs being laterally displaceable, as a whole, and means for retracting said lazy-tongs to project said levers into engagement with the wall around the flue opening to secure the flue-stopper in place, the lateral displacement of the lazy-tongs operating to accommodate said lazy-tongs to a wall of varying thickness around the flue opening.
7. In a flue-stopper, the combination with a cover-plate for the flue opening in a wall, of a lazy-tongs comprising diverging links hinged at one end to the central part of the cover-plate and crossed levers pivoted together at their intersection hinged at their inner ends to the free ends of said links respectively, said lazy-tongs being laterally displaceable as a whole, and a rotatable rod loosely mounted in the cover-plate and having a pivoted screw-threaded connection with the crossed levers at their intersection, the rotation of the rod operating to contract the lazy-tongs to project said levers into engagement with the wall around the flue opening to secure the flue-stopper in place, the loosely mounted rod and laterally displaceable lazy-tongs operating to accommodate the flue-stopper to a wall of varying thickness around the flue opening.
8. In a flue-stopper, the combination with a cover-plate for the flue opening in a wall, of diverging links hinged at one end to the central part of the cover-plate, crossed levers pivoted together at their intersection and hinged at their inner ends to the free ends of said links respectively, wall-engaging hooks extending laterally from the outer ends of said levers, a threaded plate pivoted on the common pivot of said lever, and a screw-rod extending through the cover-plate, said screw-rod engaging said threaded plate, the rotation of the screw-rod in one direction operating to move the threaded plate toward the cover-plate to retract the extended levers and links and to open the outer ends of the levers to project laterally the hooks carried thereby over the inner face of the flue wall to be pulled against the same to hold the cover-plate in place over the flue opening.
9. In a flue-stopper, the combination with a cover-plate for the flue opening in a wall, of a lazy-tongs comprising diverging links hinged at one end to the central part of the cover-plate and crossed levers pivoted together at their intersection hinged at their inner ends to the free ends of said links respectively, said lazy-tongs being angularly displaceable as a whole around the pivotal connection of the links with the cover-plate, elongated wall-engaging hooks extending laterally from opposite sides of the lazy-tongs from the outer ends of said levers, a threaded plate pivoted on the common pivot of said levers, and a screw-rod extending through a central opening in the cover-plate and having limited movement therein, said screw-rod engaging said threaded plate and angularly movable in the central aperture of the closure-plate to accommodate the angular displacement of the lazy-tongs as a whole, the rotation of the screw-rod in one direction operating to move the threaded plate toward the cover-plate to retract the lazy-tongs to project laterally the hooks over the inner face of the flue wall to be pulled against the same to hold the cover-plate in place over the flue opening.
10. In a flue-stopper, the combination with a cover-plate for the flue opening in a wall, of diverging links hinged at one end to the central part of the cover-plate, crossed levers pivoted together at their intersection and hinged at their inner ends to the free ends of said links respectively, wall-engaging hooks extending laterally from the outer ends of said levers, and means for retracting the jointed links and levers to open the latter to project the hooks over and against the inner face of the wall to hold the cover-plate in place over the flue opening.
11. In a flue-stopper, the combination with a cover-plate for the flue opening in a wall, of a lazy-tongs comprising diverging links hinged at one end to the central part of the cover-plate and crossed levers pivoted together at their intersection hinged at their inner ends to the free ends of said links respectively, said lazy-tongs being angularly displaceable as a whole around the pivotal connection of the links with the cover-plate, elongated wall-engaging hooks extending laterally from opposite sides of the lazy-tongs from the outer ends of said levers, and means for retracting said lazy-tongs to open the pivoted levers to project laterally the hooks over the inner face of the flue wall and to pull the hooks against such face, the angular displacement of the lazy-tongs and the elongated hooks operating to accommodate a wall of different thickness on opposite sides of the flue opening.
12. In a flue-stopper, the combination of a cover-plate for the flue opening in a wall, means mounted on said plate to extend into the flue opening and engage the wall in which said opening is formed to secure said plate in position, said securing means being loosely connected to said plate and thereby adapted to automatically assume a position

to accommodate irregularities in the flue opening wall engaged by said securing means.

13. In a flue-stopper, the combination of a cover-plate for the flue opening in a wall, means mounted on said plate to extend into the flue opening and engage the wall in which said opening is formed to secure said plate in position, said securing means being

pivotaly connected to said plate and thereby adapted to automatically assume a position to accommodate irregularities in the flue opening wall engaged by said securing means. 10

15 In testimony whereof I have signed this specification.

WILBUR R. CARROLL.
